UNITED STATES PATENT OFFICE.

WASHINGTON BALLARD ROSE, OF KINGSTON, TENNESSEE.

CHURN.

No. 806,919.

Specification of Letters Patent.

Patented Dec. 12, 1905.

Application filed April 22, 1903. Serial No. 153,845.

To all whom it may concern:

Be it known that I, WASHINGTON BALLARD ROSE, a citizen of the United States, residing at Kingston, in the county of Roane and State of Tennessee, have invented a new and useful Churn, of which the following is a specification.

The invention relates to improvements in churns.

10 The object of the present invention is to improve the construction of churning and to provide a simple and comparatively inexpensive one capable of being operated at the expenditure of a minimum amount of power and adapted to effect a rapid production of butter.

15 A further object of the invention is to enable a plurality of churn-dashers to be simultaneously operated for churning in a plurality of churn bodies or receptacles and to provide a system of springs adapted to operate successively to assist both the up and down movement of the churn-dashers.

With these and other objects in view the invention consists in the construction and novel combination and arrangement of parts hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

35 In the drawings, Figure 1 is a perspective view of a churn constructed in accordance with this invention. Fig. 2 is a vertical longitudinal sectional view of the same. Fig. 3 is a vertical transverse sectional view. Fig. 4 is a horizontal sectional view on the line 4-4 of Fig. 3. Fig. 5 is a horizontal sectional view on the line 5-5 of Fig. 3. Fig. 6 is a detail view of one of the cross-heads. Fig. 7 is a detail view illustrating another means for securing the dasher rods or stems to the cross-heads.

40 Like numerals of reference designate corresponding parts in all the figures of the drawings.

45 11 designate similar churn bodies or receptacles provided with covers 2, having central openings, through which pass dasher rods or stems 3 of dashers 4. The churn bodies or receptacles, which may be of any desired construction, are provided at the central open-

ings of their covers with upwardly-extended funnels 5, adapted to return to the churn any liquid carried upward by the dasher-rods. The covers of the churn bodies or receptacles 60 may be secured in place by hooks 6 or any other suitable fastening device, and the funnels may be mounted on the covers in any desired manner. The churn bodies or receptacles are arranged within a cabinet or casing 65 7, which protects them from dust during the operation of churning and which are provided at the front and back with bearings 8, arranged in pairs and receiving the ends of similar four-throw crank-shafts 9. Each four-throw 70 crank-shaft is provided with a central crank-bend 10 and a pair of diametrically oppositely arranged crank-bends 11, and the said shaft is also provided at each side of the central crank-bends 10 and 11 with side crank-bends 75 12 and 13, arranged in planes at right angles to the planes of the central crank-bends 10 and 11. The side crank-bends 12 and 13 are arranged at diametrically opposite points, as clearly shown in Fig. 1 of the drawings. The 80 dashers reciprocate in opposite directions and are reversely arranged, as shown in Fig. 2, whereby when one dasher is at the limit of its upward movement the other dasher will be at the limit of its downward movement. Four 85 pairs of coiled springs are employed for assisting the operation of each dasher and are successively brought into action by the rotation of the four-throw crank-shafts. The four-throw cranks are reversely arranged, and the 90 central double crank-bends 10 extend in opposite directions when they are disposed horizontally, as shown in Fig. 1. The dasher-rods, which have their upper ends reduced, are secured by removable pins or keys 14 in central openings 15 of cross-heads 16. When it is desired to remove the churn body or receptacle after the operation of churning has been completed, the pin or key 14 is removed and the dasher drops to the bottom of the churn- 95 body. The cabinet or casing is provided at each end with a door 17, hinged at the back and having a suitable fastening device at the front and adapted to afford access to the interior of the cabinet or casing. The cross- 100 head 16 is located centrally above the churn-body, and its ends 18 are reduced and arranged in vertical ways of the casing or cabinet. The casing or cabinet is provided at the front and back with interior vertical ways 19, preferably formed by bars or pieces secured to the inner faces of the front and rear walls of the 105

casing or cabinet and spaced apart to receive the ends of cross-heads. A pair of end cross-heads 20 and 21 are arranged beyond each of the dasher-rods, and an inner cross-head 22 is 5 arranged at each churn-body. A pair of coiled springs 23 are secured at their upper ends to the terminals of each of the cross-heads, and the lower ends of the springs are suitably secured to the bottom of the cabinet or casing. 10 The springs which are secured to the cross-heads of the dashers tend to draw the same downward, and thereby effect the downstroke of the dashers. The cross-heads are connected by cords with the crank-bends of the crank-shafts, as hereinafter explained, and when the crank-shafts are rotated the springs will be 15 successively brought into action to assist the reciprocation of the dasher, and as soon as one set of springs becomes inert another set will 20 be thrown into action, four sets being operated at each revolution of the crank-shaft. When the dasher is down, as shown at the right-hand end of Figs. 1 and 2 of the drawings, the central double loop 10 of the corresponding crank-shaft is arranged horizontally 25 and is extended outward. This central crank-bend 10 is connected by a pair of cords 24 with the adjacent outermost cross-head, and the diametrically opposite crank-bends 11 are connected by cords 25 with the inner cross-head 22. The lowermost cranks 12 are connected by cords 26 with the cross-head of the dasher-rod, and the uppermost cranks 13 are connected by cords 27 with the outer cross-head 20. The 30 cords of the crank-shaft at the left-hand end of the churn in Fig. 2 are arranged in the positions, or rather in a corresponding position, when the dasher is at the lowermost limit of its stroke—that is, when the double crank 10 40 is extended horizontally to the right in Fig. 2 the central crank 10 will be reversed and will extend to the right. The cords 28 will then extend vertically to the adjacent cross-head 22, and the cords 29 of the diametrically opposite crank-bends will then extend vertically 45 to the adjacent outermost cross-head 21. The cords 30 of the dasher cross-head are connected to one set of the vertically-aligned cranks, and the cords 31 of the adjacent outer cross-head 50 30 are connected with the outer set of the vertically-aligned cranks. However, as shown in Fig. 2, at the left-hand end thereof the cords are reversed by reason of the crank-shaft being disposed in a diametrically opposite 55 site position from that of the crank-shaft at the right-hand end of the churn.

The crank-shafts have keyed or otherwise secured to their ends pinions 32, which mesh with gear-wheels 33, located between the 60 pinions, as clearly shown in Fig. 1, and adapted to cause the crank-shafts to rotate in the same direction. The front gear-wheel meshes with a gear 34 of a shaft 35, which may, as 65 illustrated in the drawings, be provided with a crank-handle 36, but which may be operated

by any other suitable means. Instead of operating the churn by hand a suitable power may be employed, as will be readily understood. When the crank-handle is rotated, the crank-shafts with which the springs are connected 70 will be simultaneously rotated in the same direction, and the dashers will be reversely reciprocated, and the four sets of springs of each crank-shaft will be successively brought into action during each revolution, 75 and as rapidly as one set of springs becomes inactive another set will be brought into action, and both the upward and downward movement of the dasher will be assisted. The upward movement of the dasher results directly 80 from the upward pull of the central crank-bend, which is connected with the dasher by the flexible connection, and the downward movement of the dasher results directly from the springs, which are connected to the cross-head of the dasher. The dominant spring, or the spring under the greatest tension, as soon 85 as it passes over the top imparts a sudden impulse to the dasher either by suddenly pulling upward on the dasher or suddenly releasing 90 the flexible connection of the dasher, and an irregular or interrupted reciprocatory motion is produced, which results in a great agitation of the contents of the churn-body. This irregular reciprocation and the consequent agitation of the contents of the churn-body greatly 95 facilitate the production of butter.

The cross-heads, which are connected to the dashers, are limited in their downward movement to prevent them from striking the funnels by means of stops 37, consisting of strips covering the lower portions of the adjacent ways.

The shaft 35 is provided with the balance-wheel 35^a, which is mounted on the shaft, as 105 clearly shown in Figs. 3 and 4. This balance-wheel, which is shown at the front of the casing, may be located at any other desired point. Also the mechanism may be employed for operating washing-machines and devices 110 other than churning.

In Fig. 7 of the accompanying drawings is illustrated another means for securing the dasher rods or stems to the cross-heads. The cross-head 38 is provided with a movable section 39, hinged at one end and secured at the other end by a hook and eye or other suitable fastening device. The movable section and the body portion of the cross-bar are provided with similar recesses or grooves to form 115 the opening for the dasher rod or stem, which is provided with an annular groove to form upper and lower shoulders for engaging the cross-head.

Having thus fully described my invention, 125 what I claim as new, and desire to secure by Letters Patent, is—

1. In a churn, the combination with a dasher, a cross-head connected with the dasher, operating mechanism connected with the cross- 130

head for reciprocating the dasher, said operating mechanism being provided with coiled springs arranged to be distended at both the upward and downward movement of the dasher, and means for limiting the downward movement of the cross-head, substantially as described.

2. In a churn, the combination with a churn-body provided at its cover with a funnel, a cross-head, a dasher connected with the cross-head, operating mechanism provided with coiled springs arranged to be distended during both the upward and downward movement of the dasher, and means for limiting the downward movement of the cross-head to prevent the same from striking the funnel, substantially as described.

3. In a churn, the combination with a churn-body having a reciprocating dasher, a cross-head connected with the dasher, ways receiving the cross-head, springs located in the ways beneath the cross-head and connected with the latter to assist the downward movement of the same, means for moving the cross-head upward, and springs arranged to assist the upward movement of the cross-head, substantially as described.

4. In a churn, the combination with a churn-body having a vertically-reciprocating dasher, of a plurality of ways located at opposite sides of the churn-body, a plurality of cross-heads operating in the ways, one of the cross-heads being connected with the dasher, and operating mechanism for reciprocating the dasher, said operating mechanism being provided with springs connected with the cross-heads and arranged to be brought into action by both the upward and downward movement of the dasher, substantially as described.

40 5. In a churn, the combination with a churn-body having a dasher, of a plurality of cross-heads, one of the cross-heads being connected with the dasher, springs connected with the cross-heads, and a crank-shaft also connected with the cross-heads, and arranged to distend the springs during both the forward and downward movement of the dasher, substantially as described.

6. In a churn, the combination with a churn-body having a dasher, of a plurality of cross-heads, connected with the dasher and also located at opposite sides thereof, springs located beneath the cross-heads and connected with the same for moving the cross-heads downward, and means for raising the cross-heads, substantially as described.

7. In a churn, the combination with a churn-body having a dasher, of a plurality of cross-heads, connected with the dasher and also located at opposite sides thereof, springs connected with the cross-heads for moving the same downward, and means for moving the cross-heads upward, substantially as described.

8. In a churn, the combination with a churn-body having a dasher, of a plurality of cross-

heads, one of the cross-heads being connected with the dasher, springs for moving the cross-heads downward, and means for raising the cross-heads and for distending the springs during both the upward and downward movement of the dasher, substantially as described.

9. In a churn, the combination with a churn-body having a dasher, of a plurality of springs connected with the dasher, and means for operating the dasher and for distending the springs during both the upward and downward movement of the dasher, substantially as described.

10. In a churn, the combination of a churn-body having a dasher, a plurality of cross-heads, one of the cross-heads being connected with the dasher, springs for moving the cross-heads downward, and a crank-shaft connected with the cross-heads for raising the same and for successively bringing the springs into action, substantially as described.

11. In a churn, the combination of a churn-body having a dasher, a plurality of springs, and a crank-shaft provided with a plurality of cranks connected with the springs and with the dasher for operating the latter and for successively bringing the springs into action, substantially as described.

12. The combination of a plurality of cross-heads, springs connected with the same for moving the cross-heads in one direction, and operating mechanism for moving the cross-heads in the opposite direction and for successively bringing the springs into action, substantially as described.

100 13. The combination of a plurality of cross-heads, springs connected with the cross-heads for moving the same in one direction, and a crank-shaft having a plurality of cranks connected with the cross-heads for moving the same in the opposite direction and for successively bringing the springs into action, substantially as described.

14. The combination of a plurality of cross-heads, springs connected with the same for moving the same downward, a crank-shaft provided with a plurality of cranks, and flexible connections between the cranks and the cross-heads, substantially as described.

110 15. The combination with opposite ways, of cross-heads guided in the ways, springs for moving the cross-heads downward, a crank-shaft provided with a plurality of crank-bends and located above the cross-heads, flexible connections extending from the cranks to the cross-heads, and means for operating the crank-shaft, substantially as described.

16. The combination of a plurality of cross-heads, springs connected with the cross-heads for moving the same downward, a four-throw crank-shaft provided with crank-bends, and flexible connections extending from the crank-bends to the cross-heads, substantially as described.

17. The combination with a pair of churn-

bodies having dashers, of a plurality of cross-heads, means for connecting the dashers with the adjacent cross-heads, springs connected with the cross-heads for moving the same downward, shafts having a plurality of cranks connected with the cross-heads, and gearing connecting the shafts, substantially as described.

18. The combination of a cabinet or casing provided with opposite ways, cross-heads operating in the ways, springs housed in the ways and connected with the cross-heads for moving the same downward, crank-shafts having a plurality of cranks connected with the cross-heads for moving the same upward, gearing connecting the crank-shafts, and means for operating the gearing, substantially as described.

19. The combination of a plurality of dashers, a plurality of springs for assisting the upward and downward movement of the dashers, and operating mechanism for reciprocating the dashers, said operating mechanism being connected with the springs and distending the same at both the upward and downward movements of the dashers, substantially as described.

20. In testimony that I claim the foregoing as my own I have hereto affixed my signature in the presence of two witnesses.

WASHINGTON BALLARD ROSE.
